UNITED STATES PATENT OFFICE.

WALTER McDERMOTT, OF ORANGE, NEW JERSEY.

ORE-CONCENTRATOR.

SPECIFICATION forming part of Letters Patent No. 292,245, dated January 22, 1884.

Application filed February 26, 1883. (No model.)

To all whom it may concern:

Be it known that I, WALTER McDERMOTT, a subject of the Queen of Great Britain, residing at Orange, in the county of Essex and 5 State of New Jersey, have invented new and useful Improvements in Ore-Concentrators, of which the following is a specification.

My invention relates to that class of fine-ore or "slime" concentrators in which the 10 pulp or crushed ore in water is distributed regularly on a table or separating-surface, and is there exposed to the cleansing action of clear water, which washes off the lighter or waste rock, leaving the heavy mineral adhering to the surface, from which it is afterward 15 washed or brushed off into a special receptacle.

In the accompanying drawings, Figure 1 is 20 an elevation partly in section, and Fig. 2 is a plan view, of my improved machine.

In the drawings, A is the surface or table on which the separation or concentration is effected. This table A, which I prefer to make in the form of a cone having a very 25 small height, is supported by the collars B and B' on the hollow shaft C in such a way that the shaft C can revolve freely in them. The vertical hollow shaft C is supported at its lower end, which is closed by the step T, 30 and at its upper end it revolves in a bearing, M, which also forms a water-tight coupling connecting the water-pipe D with the hollow shaft C. Just at the highest part of the table A a circular pipe, E, which is provided 35 with cocks at short intervals, is attached to and connected with the hollow shaft C. The circular feed-box F with the spout F' is fixed to the shaft C above the pipe E.

G is a launder, which supplies the feed-box 40 F with pulp. Three circular launders, H H', H'', are situated just below the lower edge of the table A, which slightly overhangs the inner launder, H. The upper edges of these launders are at all points equidistant from the 45 lower edge of the table A, while their bottoms are given a fall in each direction from one point to the place of discharge at the opposite side of their circumference, in order to create a flow of the material falling into them 50 to the place of discharge.

To the under side of the table A, at any convenient point, is fixed a lug, I, to which is attached the connecting-rod K from a small 55 crank, J, on a counter-shaft at one side of

the machine. At any convenient position, as 55 at L, are gears for driving the hollow shaft C.

P and P' are adjustable deflecting-plates, which are carried by the arms O O, attached to a collar, Q, beneath the feed-box F, or to the said feed-box, or to any convenient place on 60 the shaft C. These arms O are secured to the collar Q by bolts passing through slots in said collar, so that the plates P may be adjusted as to operative position by passing one plate or section under the next one. 65

The operation of the machine is as follows: The shaft C is slowly revolved by the gears L, and carries with it the feed-box F, circular jet-pipe E, and the arms O O with the deflecting-plates P P'. At the same time the table A 70 receives a gentle shaking motion by the action of the crank J and connecting-rod K, which give the table a short alternating rotary movement on its axis about the hollow shaft C. As the shaft C revolves, the pulp in the feed-box F 75 flows down through the spout F' onto the table A, where it is subjected to the shaking produced by the crank J and to the washing action of the water from the jets in the circular pipe E, which follows the spout F' in 80 its revolutions. The water for these jets is supplied by the pipe D to the hollow shaft C, and thence it passes to the pipe E and the cocks with which it is provided. The shaking and washing to which the pulp is sub- 85 jected on the table A spreads the pulp over its surface, and the lighter waste rock, being kept suspended by the shaking in the water with which it is mixed, is washed down over the edge of the table A into the inner launder, 90 H, while the heavier mineral settles on and adheres to the surface of the table A, which is covered with smooth wood or rubber, the shaking motion of the table being sufficiently gentle and uniform not to disturb the adhesion of the particles of ore to the table A after they have once settled onto its surface. 95

The series of jets of water from the circular pipe E are so regulated that the first jets which strike the slime or fine ore after it is deposited on the table A are comparatively light, while the succeeding jets have a regularly-increasing force to the end of the series. The first of the series of jets washes away the light waste matter into the launder H, leaving the heavy 100 clean mineral settled on and adhering to the surface of the table A, from which it is washed by the more powerful streams from the last 105

of the series of jets from the pipe E. This series of jets may be so adjusted as to deal with slimes which contain minerals of different specific gravities, as well as those which 5 contain but a single mineral, and not only to cleanse them of the waste rock and earthy matter, but also to separate the denser minerals from the lighter with a considerable degree of precision. This is effected by so 10 regulating the force of the jets in the pipe E by means of the cocks that they shall first wash away the light waste matter, then the lighter mineral matter, and lastly the heaviest mineral.

15 In order that each of the matters thus separated on the table A may be delivered and kept apart by itself, I arrange deflecting-plates P P' in such a way that they throw the minerals of different specific gravity into separate 20 launders as they are washed off the table A. These plates P P', which may be of sheet-iron or any other suitable material, are portions of annular plates, and are so placed that their inner edges are just below and extend a short 25 distance under the edge of the table A. The plate P is little wider than the inner launder, H, and its outer edge projects slightly over the launder H', so any material that is washed off the table A onto the deflecting-plate P will 30 be carried over the waste launder H and be deposited in the launder H' by itself. In the same way the plate P' is made wide enough to extend across the launders H and H' and to discharge all matter washed onto it into the 35 outer launder, H''. These deflectors (of which there are two, P P', shown in the drawings) may be so made in sections, one section sliding under the other in the direction of their length, that they may be made to include a 40 greater or less drainage-surface of the table A, thus adapting them to different grades of ores and conditions of working.

If it is desired, the arms O O may be made 45 hollow and provided with jets like the pipe E, and, being also connected with the hollow shaft C, can be used to assist in washing off the cleaned ore. Brushes may also be attached to the arms O O, to assist in clearing the table A of the concentrated ore.

50 If the machine is to be used for concentrating slimes containing but one mineral, or when it is only desired to free a mixture of different minerals from the waste matter, only a single adjustable deflecting-plate, as P, is required, 55 and the outer launder, H'', may be dispensed with. On the other hand, it may be desirable to effect a number of separations, when two or more adjustable deflecting-plates may be used with a corresponding number of launders.

60 By the use of the apparatus just described, the process of concentrating slimes or other fine ores becomes a continuous one, and by varying the amount of the shake given to the table A, the proper regulation of the water-jets 65 of the pipe E, and the adjusting of the deflectors P P', slimes of different grades and those containing mixtures of several minerals may

be rapidly and easily cleaned of all waste matter and separated.

Another advantage of this apparatus is, that 70 it requires much less water to operate it than other concentrators of the same class, and at the same time I am enabled to use a separating-table of a much smaller pitch than usual, both being of great importance in reducing 75 the loss of valuable ore, besides making the process of concentration much more regular and thorough than can be attained on a table which has a steep pitch.

I am aware of the English Patents Nos. 399 80 of 1864, and 3,418 of 1875, and make no claim to anything shown therein.

What I claim, and desire to secure by Letters Patent, is—

1. The combination, with a conical table 85 flaring outwardly and downwardly, of the pulp and water distributers, a deflector adjustable as to length, the launders arranged around the outer edge of the table, and mechanism whereby the pulp and water distributers and the deflector are moved in unison, 90 substantially as described.

2. The combination of a conical table, the pulp and water distributers, and the launders with an adjustable deflector revolving around 95 the outer edge of and moving independently of the table, substantially as described.

3. The combination, with a central shaft, a feed-box, and water-distributer, of a conical table loosely fitted to move independently of 100 and be supported by said shaft, and mechanism, substantially as described, for revolving the shaft and giving the table a shaking motion independently of the motion of the shaft supporting it, as and for the purposes set 105 forth.

4. The combination, with a central shaft, of the feed-box, water-distributer, deflector, and the conical table, all supported on said central shaft, and the table constructed to be 110 moved independently of said shaft, and mechanism, substantially as described, for giving said shaft, feed-box, water-distributers, and deflector a continuous rotary motion, and the table a shaking motion, substantially as and 115 for the purpose specified.

5. The combination, with the shaft C, of a conical table provided with collars B B', loosely encircling said shaft, one of said collars having the upper part of the conical table attached thereto, and the other receiving the stays supporting the table, substantially as described.

6. The combination, with the oscillating table A, the shaft C, revolving independently 125 of the table, and constructed and arranged to support and guide it, and mechanism, substantially as described, for revolving the shaft and giving the table a shaking motion independently of the shaft supporting it, as set 130 forth.

Witnesses: WALTER McDERMOTT.
